FREDERICK MAX PORITZ, OF NEW YORK, N. Y., ASSIGNOR TO ARTISTIC BRASS & BRONZE WORKS, INC., OF NEW YORK, N. Y., A CORPORATION OF NEW YORK.

DESIGN FOR A LAMP BASE OR SIMILAR ARTICLE.

Application filed February 23, 1927. Serial No. 20,857. Term of patent 3½ years.

To all whom it may concern:

Be it known that I, FREDERICK MAX PORITZ, a German citizen, and a resident of the borough of Manhattan, city, county, and State of New York, have invented a new, original, and ornamental Design for a Lamp Base or Similar Article, of which the following is a specification, reference being had to the accompanying drawing, forming a part thereof.

Fig. 1 of said drawing is a plan view of a lamp base of my new design showing only

a portion of the ornamentation of the base member in detail, it being understood that the balance of the unornamented portion is merely a repetition of that portion more fully shown.

Fig. 2 is a side elevational diagrammatic outline of the lamp base shown in Fig. 1 for the purpose of illustrating contour.

I claim:

The ornamental design for a lamp base, or similar article, as shown.

FREDERICK MAX PORITZ.
